Primary Examiner — Clare E Heflin(74) *Attorney, Agent, or Firm* — Wood Herron & Evans LLP(57) **CLAIM**

The ornamental design for a surface mount luminaire, as shown and described.

DESCRIPTION

FIG. 1 is an isometric view of a surface mount luminaire showing our new design;

FIG. 2 is a top view thereof;

FIG. 3 is a front view thereof; and,

FIG. 4 is a bottom view thereof.

The rear view, right side view and left side view are identical to the view of FIG. 3.

The broken dash lines in the figures are for illustrative purposes only and represent non-claimed environmental subject matter. Neither the portions of the invention shown in broken dash lines nor the broken dash lines themselves form any part of the claimed design.
